United States Patent Office.

GEORGE TRAYSER, OF INDIANAPOLIS, INDIANA.

Letters Patent No. 66,653, dated July 9, 1867.

IMPROVEMENT IN PIANOS.

The Schedule referred to in these Letters Patent and making part of the same.

TO WHOM IT MAY CONCERN:

Be it known that I, GEORGE TRAYSER, of Indianapolis, Indiana, have invented certain new and useful Improvements in Pianos; and I do hereby declare the following to be a full, clear, and exact description of the same, reference being had to the drawings which accompany this specification, forming part of the same, and to the letters of reference marked thereon.

Figure 1 is a perspective view of my said improved piano.

Figure 2 is a bottom view of the same, showing the framework of the same.

Figure 3 is a view of the metallic frame of the piano with its bridges.

Figure 4 is a view of the bottom of the sounding-board of my piano.

Figure 5 is a top view of the same.

Like letters refer to like parts of the improvement.

My invention consists, first, in the peculiar construction of the bottom or floor, which consists in a lattice or net-work framing, giving greater strength, and obviating contraction and expansion from changes in temperature; second, in making the sounding-board in an arched form at its broad end, and in the form and manner of attaching the ribs securing and sustaining the arch; third, in providing the angular edge of the sounding-board with a metallic stay or brace, which is provided with a projection closely fitting and secured to the said angular edge of the sounding-board, giving it greater strength and rigidity; fourth, in providing the sounding-board with a curved stay-bar traversing the central cross-section of the same; fifth, in constructing the metallic frame with one or more ribs or braces across its length at or near its centre, to prevent its being warped or sprung by the tension of the strings; sixth, in providing the said metallic frame with recesses into which bridges of wood or other suitable material are inserted to receive the bearing of the strings, and in so arranging the strings that those composing the upper and lower octaves are nearly at right angles with each other.

The effect of the general arrangement and construction of the parts as described is to give greater strength to the instrument and to equalize the strain upon the same, producing a fuller volume of sound of the highest and purest quality, and of uniform strength in all the keys.

In Plate 1, fig. 1, A A represent the body of a piano of ordinary construction. B is the metallic frame or bed-plate. C is the sounding-board, and D is the upper surface of the bed or bottom of the same. a a a are bridges of wood or other suitable material fitted into recesses or cavities in the metallic frame B, upon which the strings i i i rest. H' H'' are longitudinal openings in the plate B to receive the bridges H H, which are attached to the sounding-board C. B' is a central cross-brace or rib extending from back to front, and forming a part of said plate B.

In Plate 2, fig. 2, A A represent the body of the piano, in which d d d d are longitudinal pieces of timber, and c c c c are similar pieces of timber suitably framed together, and which form a cross-sectional framing, constituting a series of chambers, F F F F, possessing reverberating qualities, the series of chambers being enclosed by the upper flooring D and the bottom flooring E.

In the drawing, Plate 2, fig. 2, is shown a section of the framing with a portion of the bottom E removed.

In Plate 3, fig. 3, is shown the metallic bed-plate B. It will be seen that the bridges a a a receive the bearings of the strings upon their upper surfaces, while the bridge a' is inverted, the recess of the plate B being so constructed as to receive the bridge from the under side, and the pressure of the strings being from underneath, as is shown at a'. The strings i i in the lower octave, and the string i' in the upper octave, it will be seen, are nearly at right angles with each other, which arrangement serves to counteract the strain of each upon the frame.

In Plate 4, fig. 4, is shown the lower surface of the sounding-board C. The ribs or stays n n n n are first formed rounded or convex upon their upper edges, and the sounding-board when properly formed is laid upon a smooth surface, and the ribs n n with their convex sides or edges are placed upon the surface of the sounding-board, and sufficient power applied to the ends of each to spring or bend them to a horizontal plane, when they are each and every one, to any number which may be necessary, securely attached to the sounding-board, and upon the relaxation of the pressure the ribs assume their original position, and by this resumption compel an arched or convex form of the sounding-board, giving to it the character and quality of a violin. The angular and unsupported edge of the sounding-board is provided with metallic plate G, receiving and strengthening the

same, and producing a sonorous and continuous vibration of the cords very nearly equal to the best grand pianos. Radiating from the angular brace G, and traversing the central section crosswise of the sounding-board O, is a circular stay-brace, G', serving the purpose of strength and consistency to the sounding-board at that portion of its formation where it is most requisite. This stay-brace G' may be attached to or independent of the angular brace G.

Fig. 4², Plate 4, shows the obverse side of the angular brace G.

In Plate 5, fig. 5, is a perspective view of the upper or convex side of the sounding-board with the bridge H H' H, and showing the top or lapping edge of the angular brace G. The lag g is intended as a support for the screws or other fastenings which secure the curved brace G' to the sounding-board.

Having thus fully described my invention, what I claim as new, and desire to secure by Letters Patent, is—

1. The lattice framework *c c c* and *d d d*, composing the reverberating chambers F F F, in combination with the top casing D and bottom casing E, substantially as set forth.

2. The manner of producing a convex sounding-board by means of the curved surfaces of the ribs *n n n*, as and for the purpose described.

3. The bed-plate B, when constructed with recesses to receive wooden bridges *a*, and a suspended bridge, *a'*, and with a central cross-brace, B', said parts being arranged in relation to each other and the other parts of the bed-plate, substantially as set forth.

4. The angular brace G, curved brace G', combined with each other, and attached to a convex sounding-board, constructed and applied as and for the purposes set forth.

GEO. TRAYSER.
